UNITED STATES PATENT OFFICE

166,166

COMBINED FRAMEWORK AND PROTECTIVE
GUARD FOR A PACKAGING MACHINE

Kenneth D. Knapp, Los Angeles, Calif.

Application June 19, 1950, Serial No. 10,629

Term of patent 3½ years

(Cl. D55—1)

To all whom it may concern:

Be it known that I, Kenneth D. Knapp, a citizen of the United States, residing at Los Angeles, in the county of Los Angeles and State of California, have invented a new, original, and ornamental Design for a Combined Framework and Protective Guard for a Packaging Machine, of which the following is a specification, reference being had to the accompanying drawing, forming part thereof.

Figure 1 is a perspective view of a combined framework and protective guard for a packaging machine, showing my new design.

Figure 2 is a top plan view of the device of Figure 1.

Figure 3 is a front elevation.

Figure 4 is an end elevation as viewed from the left in Figure 2.

Figure 5 is a rear elevation as viewed from the left in Figure 4.

I claim:

The ornamental design for a combined framework and protective guard for a packaging machine, substantially as shown.

KENNETH D. KNAPP.
